ONTARIO, CANADA, ASSIGNEES TO STANDARD OIL DEVELOPMENT COMPANY, A
CORPORATION OF DELAWARE

PROCESS OF REMOVING CORROSIVE AGENTS FROM HYDROCARBON OILS

Application filed December 13, 1927. Serial No. 239,656.

This invention relates to improvements in removing foreign substances, especially corrosive agents, from petroleum oils and the like. In a preferred method of carrying out 5 the invention, a continuous stream of crude oil to be purified is heated with an alkaline solution under pressure, the alkaline solution is settled out, and the purified crude oil is piped without further treating to a crude 10 still.

An important object is to provide a continuous method for rendering petroleum oil non-corrosive before it undergoes distillation. In this way, deterioration of equipment 15 is substantially prevented and at the same time the crude oil is put in condition to yield directly a gasoline of excellent quality.

The invention will be fully understood from the following description of one method 20 of operation, read in connection with the accompanying drawing, which is a diagrammatic vertical section of an apparatus suitable for carrying out the method.

In the drawing, numeral 1 denotes a mixing column which may be of the type shown 25 in the U. S. patent to Charles Leaver, No. 1,635,718, granted July 12, 1927. Crude oil containing impurities (for example elementary sulfur, hydrogen sulfide, magnesium 30 chloride, and/or iron chloride) is supplied by pump 2 and pipe 3 to the column 1. An alkaline solution, preferably a 34° Bé. water solution of sodium hydroxide, is conveyed 35 through pipe 4 by pump 5. Pipes 3 and 4 connect with a pipe 6 which opens into column 1. This column is heated in any suitable way, as by means of steam circulated through inlet and withdrawal pipes 7 and 8. The oil is preferably preheated before entering the 40 mixing column. Heat from oil vapors evolved in the system or any other suitable source of heat may be used for this purpose.

The mixed oil and solution leave column 1 45 through pipe 9. Pressure control valves 6^a and 9^a are installed in pipes 6 and 9 respectively. The temperature of the outflowing mixture may be about 220 to 240° F. The inlet pressure is desirably about 40 to 50 lbs. per square inch and the outlet pressure about 50 20 to 30 lbs.

The mixture is discharged through pipe 9 into a settling tank 10. One or more other settling tanks 11 may be connected in series with tank 10 by a pipe or pipes 12. The alkaline solution is withdrawn through valved pipes 13 and 14 from the lower part of the settling tanks and is recirculated, so long as it retains its effectiveness, through pipe 4 and the mixing column 1. When necessary, the spent solution containing the impurities removed from the oil may be withdrawn through a branch outlet pipe 13^a and fresh solution supplied from tank 15, with which pipe 4 connects.

After settling, the oil is drawn off from the last settling tank through pipe 16 directly to the tower 17 of a crude still 18. It is preferred to maintain a superatmospheric pressure of about 10 to 20 lbs. on the oil in the settling tanks and for this purpose a pressure control valve 16^a is installed in pipe 16. The still 18 may be run with a liquid temperature of about 470° to 510° F. and a temperature of about 280° to 300° F. at the top of the tower. Gasoline distillate is taken off through pipe 19 and residual oil is withdrawn through pipe 20 to another still, or other suitable disposition.

The amount and concentration of alkaline solution required will vary with the impurities in the crude oil or distillate to be treated. Enough of the solution is supplied in all cases to remove or destroy any substances corrosive in themselves or capable of yielding corrosive products during the handling of the oil. We generally prefer to pass about equal volumes of oil and solution together through the mixing column. The solution separates readily from the oil in the settling tanks and the oil is still hot when it enters the tower.

The invention is not limited to the temperatures, pressures, and other precise conditions above referred to, but these are merely given for illustration. As a general indication of the range of permissible temperatures and pressures, it may be said that in treating crude oils such as those from the mid-continent fields, temperatures between 180° F. and 260° F. and pressures between 20 lbs.

per square inch and 100 lbs. per square inch are desirable. While the treatment described is sufficient in most cases, the use of doctor solution or other purifying agent may sometimes be required, particularly when the oil contains a large percentage of the higher mercaptans. Such auxiliary treat may be applied either before or after distillation.

Treating with hot caustic under pressure as described may be applied to reduced crudes, and the like, as well as directly to crude oils. A reduced crude or lubricating distillate, for example, may be passed continuously while still hot from the still to the treating and settling equipment, and thence to redistillation.

Various changes and alternative procedures may be made within the scope of the appended claims, in which we desire to claim all novelty inherent in the invention as broadly as the prior art permits.

We claim:

1. The method of treating crude petroleum oil to remove chlorides, elementary sulfur and hydrogen sulfide, which comprises heating a continuous stream of mixed crude oil and alkaline solution under greater than atmospheric pressure maintaining the temperatures below the cracking temperatures of the oil, reducing the pressure, continuously passing the heated mixture under reduced but greater than atmospheric pressure through enlarged zones whereby impurities are settled from the crude oil, and distilling the purified oil.

2. The method of treating crude petroleum oil to remove chlorides, elementary sulfur and hydrogen sulfide, which comprises heating a continuous stream of mixed crude oil and alkaline solution under a pressure of approximately 40-50 lbs. per square inch and a temperature of approximately 180-260° F., reducing the pressure, continuously passing the heated mixture under a pressure of approximately 20-30 lbs. per square inch through enlarged zones whereby impurities are settled from the crude oil, and distilling the purified oil.
